Inventor:

James J. Fetzer

UNITED STATES PATENT OFFICE.

JAMES J. FETZER, OF COLUMBIANA, OHIO, ASSIGNOR TO THE HERBRAND COMPANY, OF FREMONT, OHIO, A CORPORATION OF OHIO.

WRENCH.

No. 808,603.

Specification of Letters Patent.

Patented Dec. 26, 1905.

Application filed May 10, 1905. Serial No. 260,010.

To all whom it may concern:

Be it known that I, JAMES J. FETZER, a citizen of the United States, residing at Columbiana, county of Columbiana, and State of Ohio, have invented certain new and useful Improvements in Wrenches; and I do hereby declare the following to be a full, clear, and exact description of the invention, such as will enable others skilled in the art to 50 which it appertains to make and use the same.

My invention relates to wrenches, and has particular reference to an auxiliary detachable wrench-jaw whereby an ordinary nut or bolt wrench may instantly and conveniently 55 be converted into a pipe-wrench, either right or left handed.

As a further object the invention contemplates the manufacture of a unitary self-retained detachable wrench-jaw capable of instant application to either jaw of an ordinary wrench without the necessity of independent 60 fastening means.

The invention will be hereinafter described, and particularly pointed out in the 65 claims following.

In the accompanying drawings, which form part of this application, and whereon corresponding numerals of reference indicate the same parts in the several views, Figure 1 70 represents in perspective my invention applied to an ordinary nut-wrench. Fig. 2 is a perspective view of my invention detached; and Fig. 3 is also a perspective view similar to Fig. 2, but from the opposite point of observation.

Reference being had to the drawings and numerals thereon, 1 indicates a wrench-handle, 2 its outer fixed jaw, and 3 its inner adjustable jaw, all of ordinary and well-known 75 construction.

Upon the handle 1 adjacent to the fixed jaw 2, as shown by Fig. 1, is detachably secured my present invention, comprising spring side flanges 4 5, an intervening steel space-block 6, having a serrated working face 7, and a plain opposite or inner surface 8, the latter, by preference, slightly overlapped by the projecting edges of said flanges 4 and 5. The spring side flange 4, differ-

ing from the flange 5, extends upward and 50 terminates in a spring-hook or retaining member 9 for purposes which will now appear.

The use and operation of this invention may be briefly stated as follows: It being desired to convert an ordinary nut or bolt wrench into a pipe-wrench, this may be instantly accomplished by the use of my improved unitary attachment, which is clearly shown by Figs. 2 and 3 of the drawings. 55 This attachment is clipped into position upon handle 1 at a point intermediate of the jaws 2 and 3, the spring action of the upper portion 9 of the side flange 4 permitting of such instantaneous adjustment. Thereupon 60 the attachment is slid longitudinally upon its supporting-handle 1 until the projecting side flanges 4 and 5 embrace the fixed wrench-jaw 2, as shown by Fig. 1. These flanges then 65 cooperate with the upper spring-hook member 9 to snugly retain the attachment in operative position against lateral movement or other accidental displacement regardless of the strains to which it may be subjected in the course of usage. Nevertheless the attachment may be instantly removed when 70 desired by a reversal of the operation heretofore described, and obviously it may as well be replaced in a reversed position or adjacent to the adjustable wrench-jaw 3, in 75 which latter event the action of the wrench upon a pipe would be reversed.

Having thus described my invention, what I claim, and desire to secure by Letters Patent, is—

1. In a wrench the combination with an auxiliary detachable jaw having a spring-acting retaining-hook, and side flanges adapted to partially embrace one main jaw of the wrench, substantially as described.

2. In a wrench the combination with an auxiliary detachable jaw having a spring-acting retaining-hook and projecting side flanges adapted to coact with said hook to prevent accidental displacement of said auxiliary 95 jaw, substantially as described.

3. As an article of manufacture a unitary auxiliary detachable wrench-jaw, having a

spring-acting retaining-hook for engagement with a wrench-handle, and projecting side flanges for engagement with one jaw of a wrench, substantially as described.

5 4. In a wrench the combination with an auxiliary detachable jaw, having side locking-flanges, a spring-acting retaining-hook surmounting one of said flanges, and a serrated

space-block between said flanges, substantially as described.

In testimony herewith I subscribe my signature in presence of two witnesses.

JAMES J. FETZER.
